OVERLOAD RELEASE FOR REFUSE COMPACTOR

Edwin A. Schonrock, San Angelo, Tex.

Application November 3, 1955, Serial No. 544,637

15 Claims. (Cl. 214—82)

This invention comprises novel and useful improvements in an overload release for refuse compactors and more specifically relates to a construction which may be employed as a safety device to prevent breakage in the driving means such as the driving chains of refuse compacting structures such as are employed in garbage or trash trucks or the like.

The principal object of this invention is to provide a construction which may be either originally built into or subsequently applied to conventional types of refuse compactors for garbage and other trucks whereby the compacting device will be protected against breakage in the event of a predetermined overload being applied thereto, to thereby improve the operation of and reduce the cost of repairs of such devices.

A very important object of this invention is to provide an overload release connection whereby a reciprocating refuse compacting blade may be connected to a chain or other driving means in an improved manner.

Another object of the invention is to provide an overload release device in accordance with the preceding object which may be readily utilized as a component of conventional refuse compactors for trash or garbage trucks and the like in the manufacture of the same, with a minimum of alteration in the assembly.

A further object of the invention is to provide an overload release mechanism in accordance with the foregoing objects which will improve the operation of the refuse compacting assembly in order to thereby decrease the skill and the time required of the operator for compacting material in a truck body or the like; will enable the material to be stored and compacted to a predetermined degree and compression pressure with much greater accuracy and facility.

A further object of the invention is to provide an overload release mechanism in accordance with the above mentioned objects which will not interfere with the continuing backward and forward travel of the driving chain of the compactor blade, but will permit disengagement of the driving connection between the blade and the chain when a predetermined overload has been applied to the blade, and yet will in no way interfere with the retraction of the blade upon reverse movement of the chain or other blade driving means.

A still further important object of the invention is to provide an overload release mechanism as set forth in the foregoing objects wherein the wear upon the chain will be reduced by the establishing of a new connection between the blade and the driving chain at different positions thereon during subsequent release of the blade from the chain upon overloads.

Still other very important objects are to provide an overload release mechanism in compliance with the preceding objects wherein a conventional magnetic brake may be utilized; and wherein a mechanical advantage may be secured between the brake and a blade driving chain to permit the use of a smaller brake.

And a final important object of the invention to be specifically enumerated herein resides in the provision of an overload release device in accordance with the preceding objects which may be readily incorporated into

2

the driving mechanism of the drive chain of the compacting device whereby conventional compacting mechanisms may be adapted economically to attain the objects and purposes of this invention.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a side elevational view, parts being broken away and shown in vertical section, showing a conventional type of trash or garbage truck having a refuse compacting mechanism associated therewith, and to which the principles of this invention have been applied.

Figure 2 is a perspective view of the compacting blade, parts being broken away, showing the manner in which the overload release device of this invention is associated with such blade and with the blade driving chain;

Figure 3 is a detail view in vertical transverse section across a portion of the lower portion of the compacting blade as viewed from the left side of Figure 2, and showing in particular the manner in which the driving chain and the overload release device are associated with the blade;

Figure 4 is a fragmentary detail view showing in vertical longitudinal section further details of the manner in which the driving chain is associated with the overload release device and with the compacting blade;

Figure 5 is a fragmentary view in vertical longitudinal section, parts being shown in elevation, and showing a modified construction for applying the overload release device to a refuse compacting assembly; and

Figure 6 is a view similar to Figure 3 but showing a preferred modification affording a mechanical advantage between the friction brake and the blade driving chain.

In the accompanying drawings, reference is made first to the embodiment disclosed in Figures 1-4 wherein the principles of the invention are shown applied to a trash or refuse truck indicated generally by the numeral 10 and which as illustrated may consist of a trailer detachably coupled as by a fifth wheel assembly 12 to the rear portion of a tractor vehicle indicated generally by the numeral 14. Conveniently, the trailer includes a substantially cylindrical refuse receiving body 16 which is generally circular in cross section, and which at its forward end is provided with an opening 18 in its upper portion for loading material into the body. In the conventional type of refuse truck illustrated, there is provided a material compactor 20, which as shown best in Figure 2, consists of a circular plate which is disposed within the body 16 in a vertically inclined position and substantially fills the cross sectional area of the body.

This compactor is adapted to be reciprocated longitudinally of the body in order to compress or compact material towards the closed rear end of the body, from whence material is ultimately discharged or unloaded.

A power plant designated generally by the numeral 22 is mounted upon the front portion of the trailer and by suitable control means indicated at 24 is adapted to impart reciprocating travel to the compactor blade longitudinally of the body.

In the conventional trash or refuse truck illustrated, there is provided a means for reciprocating the compactor blade 20, this means comprising a chain 26. The latter is entrained over suitable support members in the form of sprocket gears 28 and is disposed with its upper flight 30 lying upon or closely adjacent to the bottom wall of the body 16. This upper flight extends entirely through the body from the front wall 32 thereof to the back wall, and emerging from the latter may extend

through a suitable guide housing 34. A driving sprocket 36 is connected with the chain 26 and is driven from the power and speed control means 24.

It will now be understood that by use of the control means 24, reversing rotation may be imparted to the chain, whereby the upper flight of the same may be reciprocated upon the bed of the truck body. By a mechanism to be now described, the compactor blade 20 is connected to the upper flight of the chain whereby the compactor will be reciprocated longitudinally of the body between the position shown in Figure 1 to a position at the extreme right hand end of the body. As the refuse or material within the body is successively compressed in the right hand end of the same, it is obvious that the reciprocating travel of the compactor blade and of the upper flight of the chain will necessarily be reduced.

Heretofore, it has been very difficult to accurately control the operation of the blade and yet secure the desired compression of the material in the body. Frequently the operator has failed in his judgment, and either reversed the travel of the chain and compactor blade too soon, thereby failing to give the desired compression to the material in the body; or has waited too long before such reversal of travel, resulting in placing undue strain upon the compactor blade and chain, and frequently causing breakage of the chain.

By the present invention, a connection is provided between the compactor blade and chain which will eliminate the above disadvantages, and will enable the blade to make its complete stroke and secure the desired compression of the material in the body since there is no danger of an overload being applied by the blade to the chain with resultant breakage of any of the parts.

Referring now more particularly to Figures 2-4 it will be seen that the compactor blade 20 includes upon what may be termed its rear face a pair of vertical webs or ribs 38 provided with suitable cross or bracing webs 40. Between the two webs 38 there is secured a transverse shaft or axle 42 which is held stationary as by a key 44. Freely rotatably journaled upon the shaft 42 is the hub 46 of a sprocket gear 48. This sprocket gear is continuously in mesh with the upper flight 30 of the sprocket chain 26. A pair of hold-down or guide sprockets 50 and 52, each freely rotatable upon axles 54 which are carried by the above mentioned webs 38 are also provided, whereby, as shown in Figures 2 and 4, the guide pulleys will hold the upper flight 30 into circumferential contact with the upper portion of the sprocket gear 48. It will be observed that the lower portion of the compactor blade 20 is provided with an upwardly extending notch or slot 56 through which the upper flight may pass.

Fixedly secured upon the stationary shaft 42 as by a set screw 58 is the hub 60 of an overload release coupling 62 which cooperates with a laterally extending drum or shoe, not shown, of the sprocket gear 48. The coupling 62 may be of any desired type and construction which is capable of having an adjustable frictional gripping action upon the sprocket gear. Thus, the member 62 may conveniently consist of an overload release coupling such as a friction brake or a magnetic brake, of various types now available upon the open market.

By the construction so far described, it will now be apparent that the compactor blade is connected to the sprocket chain by an overload release coupling or connection so that the blade is secured to the upper flight of the chain for longitudinal reciprocation therewith. However, when the compactor blade encounters a predetermined pressure, as when the desired degree of compaction has been given to the material, the coupling 62 will slip and permit continued travel of the chain without damage to the latter, and without further movement in the same direction of the compactor blade. This continued movement of the chain is permitted by the rotation of the sprockets 50, 52 and 48.

When the travel of the chain is reversed, either manually by the operator or by any desired automatic mechanism, it is obvious that the coupling 62 will be effective to immediately retract the blade therewith. The blade will then be in readiness for the next compressing or compacting stroke, and will require no adjustment for that purpose. It will thus be seen that each time the blade is caused to slip upon the chain, it will be engaged in a new position thereon, thus distributing possible wear of the chain along the length of the same.

At this point it is to be understood that in accordance with conventional practice, the compactor blade 20 is tilted backwardly from its lower end to its upper end. This facilitates the introduction of material into the body through the opening 18, upon the forward side of the blade, and as the blade in its longitudinal travel compacts the material within the body, the inclination of the blade will tend to lift the material and thus uniformly pack the same throughout the vertical height of the body.

It should be observed that by this construction the entire attachment by which the compactor blade is releasably connected to the reciprocating means, the upper flight of the cable, is carried by and housed between the pair of ribs upon the rear surface of the compactor blade in a protected, and convenient and compact manner.

The above described construction may be readily installed in compacting devices or means as originally assembled in a truck. However, it is also possible to obtain some of the advantages of this invention by providing an overload release mechanism which may be installed as an attachment or replacement in existing compacting mechanisms. For this purpose the modified construction shown in Figure 5 may be employed.

In this form, the trailer 10 previously mentioned is provided having the body 16 together with the power plant 22 having a control means for its power output as at 24.

As in the preceding embodiment, the compacting means includes a compactor blade 70 which is similar to the blade 20 except that the notch or slot 56 is omitted. In this arrangement the chain 26 is replaced by a chain 72 which is entrained over the same guide sprockets 28 previously mentioned in the same manner as set forth in connection with the preceding embodiment. However, instead of their being continuous as in that embodiment, the chain 72 has its two opposite ends secured to lugs 74 on the front side of the compactor blade at the bottom thereof, whereby the upper flight 76 of the chain will lie closely adjacent to the bottom wall of the truck body. The other end of the chain is secured as by a transverse shaft 78 between a pair of vertical webs 80, similar to the webs 38, this portion of the chain extending through an opening in the forward wall in the same manner as that shown in connection with the chain of Figure 1. A driving sprocket 82 is engaged with the chain for imparting reverse rotation thereto from the power plant whereby the upper flight of the chain will have a reciprocating movement longitudinally of the body. Interposed between the sprocket 82 and the power take-off 24 is an overload release coupling 84 which is of the same character as set forth in connection with the coupling 62.

It will thus be seen that when the compactor blade encounters a predetermined resistance, travel of the blade and of the chain is stopped since the overload release device 84 will slip as long as that resistance is encountered. The operation of this form of the invention is identical with that set forth in connection with the preceding embodiment except that instead of the slippage occurring between the compactor blade and the chain, slippage is permitted between the source of power and the driving sprocket of the chain.

Shown in Figure 6 is a preferred modification which may be employed in either of the two preceding embodiments of Figures 1-4 and Figure 5 in order to se-

cure a mechanical advantage between the brake and chain 62, 26 and 84, 72 respectively. By this arrangement, a smaller brake may be utilized or the load upon the same may be reduced.

In Figure 6, which illustrates the manner of applying this modification to the embodiment of Figures 1-4, the same numerals are employed to identify the unmodified components of construction of Figures 1-4. However, between the webs 38, in lieu of the axle 42 there is journaled and secured a shaft or axle 43 upon which is rotatably journaled a sleeve 45, comprising the hub of a pair of gears 49 and 51. The top flight 30 of the blade drive chain 26 is entrained over the gear 49, in the same manner as for the gear 48 of Figure 3.

However, the magnetic or other type of friction brake 62 is secured rigidly in any suitable manner to one of the webs 38 above the shaft 43 and is provided with a torque shaft 63 having a gear 65. The latter is disposed in line with the second gear 51 on the lay or countershaft sleeve 45, as by a sprocket chain 67.

The relative ratios of the gears 49, 51 and 65 will be so selected as to afford the desired mechanical advantage in the braking action of the brake 62 upon the chain 26.

In the preceding description, the invention has been disclosed as applied to a trailer. It is to be understood that the same is considered to be equally applicable to a truck body as well as a trailer body, and the term truck is intended to designate both a truck body and a trailer body.

It is also to be understood that although the invention has been shown as applied to a chain for reciprocating the compactor blade, any other reciprocating element could be employed, it being merely necessary that reciprocatory motion be imparted to the compactor blade and that an overload release connection be provided between the compactor blade and the reciprocating element.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

1. In a refuse truck, a body, a refuse compacting means operatively associated therewith and including a compactor extending transversely of the body and movable longitudinally within the same, reciprocating means disposed longitudinally of said body, connecting means operatively securing the compactor to the reciprocating means for movement therewith whereby the compactor will compress refuse in said body upon movement of the compactor longitudinally thereof in one direction, said connecting means normally securing the compactor to the reciprocating means but operatively disengaging the compactor from the reciprocating means when the compactor encounters a predetermined resistance to its longitudinal movement, said connecting means being mounted upon the compactor.

2. In combination with a truck body, a material compacting means operatively associated therewith and including a chain, means supporting the chain with one flight thereof disposed longitudinally in said body, means for reciprocating said flight, a compactor extending transversely of the body and within the same, connecting means operatively securing the compactor to the chain for longitudinal reciprocation therewith and responsive to a predetermined resistance to movement of the compactor for operatively disengaging the latter from the chain, said connecting means being mounted upon the compactor.

3. In combination with a truck body, a material compacting means operatively associated therewith and in-

cluding a chain, means supporting the chain with one flight thereof disposed longitudinally in said body, means for reciprocating said flight, a compactor extending transversely of the body and within the same, connecting means operatively securing the compactor to the chain for longitudinal reciprocation therewith and responsive to a predetermined resistance to movement of the compactor for operatively disengaging the latter from the chain, said connecting means including a sprocket journaled on said compactor, said flight being continuously engaged with said sprocket, an overload release means operatively associated with said sprocket for normally preventing rotation of the latter.

4. In combination with a truck body, a material compacting means operatively associated therewith and including a chain, means supporting the chain with one flight thereof disposed longitudinally in said body, means for reciprocating said flight, a compactor extending transversely of the body and within the same, connecting means operatively securing the compactor to the chain for longitudinal reciprocation therewith and responsive to a predetermined resistance to movement of the compactor for operatively disengaging the latter from the chain, said connecting means including a sprocket journaled on said compactor, said flight being continuously engaged with said sprocket, an overload release means operatively associated with said sprocket for normally preventing rotation of the latter, said sprocket and said overload release means being mounted upon a common shaft.

5. In combination with a truck body, a material compacting means operatively associated therewith and including a chain, means supporting the chain with one flight thereof disposed longitudinally in said body, means for reciprocating said flight, a compactor extending transversely of the body and within the same, connecting means operatively securing the compactor to the chain for longitudinal reciprocation therewith and responsive to a predetermined resistance to movement of the compactor for operatively disengaging the latter from the chain, said connecting means including a sprocket journaled on said compactor, said flight being continuously engaged with said sprocket, an overload release means operatively associated with said sprocket for normally preventing rotation of the latter, said sprocket and said overload release means being mounted upon a common shaft, said shaft being carried by said compactor.

6. In a refuse truck, a body, a refuse compacting means operatively associated therewith and including a compactor extending transversely of the body and movable longitudinally within the same, means for causing reciprocation of said compactor longitudinally of said body whereby the compactor will compress refuse in said body upon longitudinal movement in one direction, means carried by said compactor responsive to a predetermined resistance to movement of said compactor in said one direction for relieving said last mentioned means from further increase in load.

7. In combination with a truck body, a material compacting means operatively associated therewith and including a chain, means supporting the chain with one flight thereof disposed longitudinally in said body, means for reciprocating said flight, a compactor extending transversely of the body and within the same, connecting means operatively securing the compactor to the chain for longitudinal reciprocation therewith and responsive to a predetermined resistance to movement of the compactor for operatively disengaging the latter from the chain, said connecting means including a sprocket journaled on said compactor, said flight being continuously engaged with said sprocket, an overload release means operatively associated with said sprocket for normally preventing rotation of the latter, said overload release means comprising a magnetic brake, said brake holding said sprocket rotationally stationary relative to said flight,

8. In a refuse truck, a body, a refuse compacting means operatively associated therewith and including a compactor extending transversely of the body and movable longitudinally within the same, reciprocating means disposed longitudinally of said body, connecting means operatively securing the compactor to the reciprocating means for movement therewith whereby the compactor will compress refuse in said body upon movement of the compactor longitudinally thereof in one direction, said connecting means normally securing the compactor to the reciprocating means but operatively disengaging the compactor from the reciprocating means when the compactor encounters a predetermined resistance to its longitudinal movement, said connecting means including a gear mounted on said compactor and a means connecting said gear to said reciprocating means, a friction brake carried by said compactor and operatively connected to said gear for resisting rotation thereof.

9. In a refuse truck, a body, a refuse compacting means operatively associated therewith and including a compactor extending transversely of the body and movable longitudinally within the same, reciprocating means disposed longitudinally of said body, connecting means operatively securing the compactor to the reciprocating means for movement therewith whereby the compactor will compress refuse in said body upon movement of the compactor longitudinally thereof in one direction, said connecting means normally securing the compactor to the reciprocating means but operatively disengaging the compactor from the reciprocating means when the compactor encounters a predetermined resistance to its longitudinal movement, said connecting means including a gear mounted on said compactor and a means connecting said gear to said reciprocating means, a friction brake carried by said compactor and operatively connected to said gear for resisting rotation thereof, means producing a mechanical advantage operatively interposed between said brake and said gear.

10. In a refuse truck, a body, a refuse compacting means operatively associated therewith and including a compactor extending transversely of the body and movable longitudinally within the same, reciprocating means disposed longitudinally of said body, connecting means operatively securing the compactor to the reciprocating means for movement therewith whereby the compactor will compress refuse in said body upon movement of the compactor longitudinally thereof in one direction, said connecting means normally securing the compactor to the reciprocating means but operatively disengaging the compactor from the reciprocating means when the compactor encounters a predetermined resistance to its longitudinal movement, said connecting means including a gear mounted on said compactor and a means connecting said gear to said reciprocating means, a friction brake carried by said compactor and operatively connected to said gear for resisting rotation thereof, means producing a mechanical advantage operatively interposed between said brake and said gear, said last mentioned means comprising a reduction gearing assembly.

11. In a refuse truck, a body, a refuse compacting means operatively associated therewith and including a compactor extending transversely of the body and movable longitudinally within the same, reciprocating means disposed longitudinally of said body, connecting means operatively securing the compactor to the reciprocating means for movement therewith whereby the compactor will compress refuse in said body upon movement of the compactor longitudinally thereof in one direction, said connecting means normally securing the compactor to the reciprocating means but operatively disengaging the compactor from the reciprocating means when the compactor encounters a predetermined resistance to its longitudinal movement, said connecting means including a gear mounted on said compactor and a means connecting said gear to said reciprocating means, a friction brake

carried by said compactor and operatively connected to said gear for resisting rotation thereof, means producing a mechanical advantage operatively interposed between said brake and said gear, said last mentioned means comprising a reduction gearing assembly, said assembly including a countershaft carried by said compactor, a pair of connected gears on said countershaft, means operatively connecting one of said pair of gears to the first mentioned gear and the other of said pair of gears to said brake.

12. In combination with a truck body, a material compacting means operatively associated therewith and including a chain, means supporting the chain with one flight thereof disposed longitudinally in said body, means

15 for reciprocating said flight, a compactor extending transversely of the body and within the same, connecting means operatively securing the compactor to the chain for longitudinal reciprocation therewith and responsive to a pre-

20 determined resistance to movement of the compactor for
operatively disengaging the latter from the chain, said
connecting means including a sprocket journaled on said
compactor, said flight being continuously engaged with
said sprocket, an overload release means operatively
associated with said sprocket for normally preventing
25 rotation of the latter, said overload release means com-
prising a magnetic brake, said brake holding said sprocket
rotationally stationary relative to said flight, means pro-
ducing a mechanical advantage operatively interposed
between said brake and said sprocket.

30 13. In a refuse truck having a body and a refuse compactor operatively associated therewith, reciprocating means disposed longitudinally of said body and operatively secured to said compactor for imparting reciprocation thereto longitudinally of said body, a source of power

35 including a sprocket operatively connected to said reciprocating means for causing reciprocation thereof, a friction brake, overload release means including said brake operatively interposed between and connecting said source of power and said compactor for disengaging the
40 latter from the reciprocating means when the compactor encounters a predetermined overload.

14. The combination of claim 6 wherein said means encounters a predetermined overload.

44. The combination of claim 3 wherein said means
for causing reciprocation of said compactor is received
through openings in said compactor and is relatively
45 movable therein.

49 15. In a refuse truck, a body, a refuse compacting

means operatively associated therewith and including a compactor extending transversely of the body and movable longitudinally within the same, means for causing reciprocation of said compactor longitudinally of said body whereby the compactor will compress refuse in said body upon longitudinal movement in one direction, means carried by said compactor responsive to a predetermined resistance to movement of said compactor in said one direction for relieving said last mentioned means from further increase in load, said compactor including a space in the lower portion thereof and lying between the front and rear confines of the compactor, said means carried by said compactor being disposed in said space, said compactor having openings from its front and rear into said space, said means for causing reciprocation of said compactor being movably extended through said openings.
